DESIGN FOR A CANISTER

George W. Stallings, Jackson, and George W. Walker, Pleasant Ridge, Mich., assignors, by direct and mesne assignments, to A. Kreamer, Incorporated, New York, N. Y., a corporation of New York

Application May 22, 1936, Serial No. 62,784

Term of patent 14 years

To all whom it may concern:

Be it known that we, George W. Stallings and George W. Walker, both citizens of the United States, the former a resident of the city of Jackson, in the county of Jackson and State of Michigan, and the latter a resident of the city of Pleasant Ridge, in the county of Oakland and State of Michigan, have invented a new, original, and ornamental Design for Canisters, of which the following is a specification, reference being had to

the accompanying drawing, forming part thereof.

Figure 1 is a front elevation of the canister, showing our new design;

Figure 2 is a side elevation; and

Figure 3 is a top plan view thereof.

We claim:

The ornamental design for a canister, as shown.

GEORGE W. STALLINGS.

GEORGE W. WALKER.
